(57) **CLAIM**

The ornamental design for a portion of a socket, as shown and described.

DESCRIPTION

FIG. 1 is a perspective view of the portion of a socket showing my new design;

FIG. 2 is a front elevational view thereof (the rear elevational view is a mirror image of the front elevational view); FIG. 3 is a left side elevational view thereof (the right side elevational view is a mirror image of the left side elevational view);

FIG. 4 is a top plan view thereof;

FIG. 5 is a bottom plan view thereof; and,

FIG. 6 is an enlarged view, for clarity purpose only, to show the rectangular and recessed contour of portion of the portion of a socket showing my new design.

The broken lines in the drawings depict environmental subject matter only and form no part of the claimed design.
